UNITED STATES PATENT OFFICE.

CHARLES H. TISE, OF WINSTON, NORTH CAROLINA.

WATER-ELEVATOR.

SPECIFICATION forming part of Letters Patent No. 309,746, dated December 23, 1884.

Application filed March 1, 1884. (No model.)

To all whom it may concern:

Be it known that I, CHARLES H. TISE, a citizen of the United States, residing at Winston, in the county of Forsyth and State of North Carolina, have invented new and useful 5 Improvements in Water-Elevators, of which the following is a specification.

This invention relates to that class of water-elevators in which buckets carried by an endless traveling chain or belt serve to raise the water from the well and deliver it into a trough in the well-curb.

The object of the invention is to provide a water-bucket of a novel construction, which 15 is attached to an endless chain or belt or other medium for raising and lowering the same, and is so shaped as to embrace or straddle the wheel or pulley provided at the top of the well for the reception and guidance of the endless chain or 20 belt carrying the bucket or buckets. By this arrangement the bucket can have a larger water-holding capacity than ordinary buckets without increasing the diameter of the well and its curb. Another feature of the curb is a novel 25 friction-brake for the guide wheel or pulley over which the bucket-carrying chain passes, said brake being a swinging arm arranged in the same relative position to the guide-wheel as the construction shown in Patent No. 273,914, 30 dated March 13, 1883, but embracing a somewhat different or improved manner of mounting said brake-arm. The latter, while specially adapted for the guide wheel or pulley of a water-elevator, can also be applied to all kinds 35 of wheels, drums, and windlasses used in hoisting apparatus.

The invention consists in the construction and combination of parts, which will be hereinafter more fully described, and set forth in 40 the claims.

In the drawings, Figure 1 is a vertical sectional view of a well curb or casing, showing the guide-wheel and endless chain in elevation and one of the water-buckets in section, said bucket 45 being in the position it assumes just before discharging its contents. Fig. 2 is a plan or top view of the well-curb, guide-wheel, endless chain, and bucket. Fig. 3 is a face view of the guide-wheel, partly in section, showing 50 the swinging brake-arm in position. Fig. 4 is a longitudinal sectional view of the guide-

wheel and the bearing for supporting the brake-arm and crank-shaft or winch of the guide-wheel. Fig. 5 is a perspective view of the bearing for the brake-arm; Fig. 6, a 55 transverse section of the water-bucket. Fig. 7 is a longitudinal section of the same. Fig. 8 is a perspective view of said water-bucket and part of its carrying-chain. Fig. 9 is a detail view showing the shape of the carrying-chain for the water-bucket.

The letter A designates the casing or curb of a well, in which operates an endless chain or apron, B, carrying any suitable number of buckets, C, for raising water from the bottom 65 of the well and delivering it into a spout or trough, D, on the well-curb. The endless chain B passes over a guide wheel or pulley, E, which is arranged in the well curb or casing, and is fitted on a transverse shaft, F, having its ends 70 journaled in boxes on said curb. The shaft F has a suitable crank-arm, F', or handle for turning the same and imparting the proper traveling movement to the endless chain carrying the buckets. One of the bearings or boxes 75 of the shaft is elongated or is constructed in the form of a tube, G, which has a flange, g, for attaching it to the well-curb, as is clearly shown in Figs. 2 and 5. This elongated bearing or tube has an axial opening for the passage of the shaft, and is formed at its inner end with an eccentrically-disposed projection, G², as is shown in Figs. 3, 4, and 5. This eccentric part of the bearing G is encircled by the hub or apertured inner end of a swinging 85 brake-arm, H, the outer end of which engages with the inner periphery of a ring-shaped flange, e, projecting from the side of the wheel or pulley E. It is evident that by hanging said brake-arm in the eccentric manner shown 90 that the movement or rotation of the wheel or pulley E can take place in one direction; but that a reverse movement thereof is prevented by the forcible binding or contact of the brake-arm against the ring-flange e.

It may be stated that the operation of the brake-arm is substantially the same as is described in the Patent No. 273,914; but I have in the present instance devised a more perfect and secure manner of mounting said brake-arm. The periphery of the pulley or wheel E is grooved and also has transverse notches for 95 100

the reception and retention of the links comprising the endless chain or bucket-carrier. This chain is preferably composed of bar-shaped links b , which have interlocking end sleeves and forked portions b^2 and b^3 , through which are passed fastening-rivets b^4 , as is seen in Fig. 9.

The buckets for raising the water from the well and delivering it into the discharge-trough of the well-curb are composed of a cylindrical shell or body, C, which has a segmental opening or chamber, H' , in its middle portion that conforms in shape to the periphery of the guide wheel or pulley E. The lateral walls H^2 of this chamber serve to divide the shell or body into two compartments, which, however, are in communication with each other by the space or opening left between the curved bottom wall of the chamber H' and the inner periphery of the shell of the bucket. The latter is connected with the chain by fitting the links thereof at the ends of the chamber H' , and securing them in place by means of suitable rivets passed through the side walls, H^2 , and the links, as is shown in Figs. 6 and 7. The bottom of the segmental chamber, which, it may be incidentally stated, is of the length of two chain-links, has a rib, H^2 , that engages with the notched periphery of the wheel or pulley E and prevents the bucket from slipping backward thereon. The bucket has two openings, h^3 , one for each interior water-chamber thereof, and directly opposite to said opening is a third opening, h^4 , which has a valve, h^5 , as is shown in Fig. 6. The valve opens in an inward direction, as is shown in Fig. 1, and serves to uncover its opening as the bucket is taking in water, or is being filled through the other openings, h^3 . It is evident that when the bucket is descending into the water that the openings h^3 are brought lowermost and that the air displaced by the incoming water is permitted to escape through the opening h^4 , which for the time being is uppermost. When the bucket is full and is ascending, the position of the bucket is

reversed and the weight of the water serves to hold the valve h^5 closed, as is shown in Fig. 6. As soon as the bucket has passed over the top of the wheel or pulley E, and is commencing to descend, the openings h^3 are brought lowermost and the water flows out through the same into the trough or gutter of the well-curb, as is shown in Fig. 1.

Having thus described my invention, what I claim is—

1. In a water-elevator, the combination of a bucket having a central chamber and water-chambers on each side thereof with a carrier chain or belt and a guide or supporting wheel adapted to enter the central chamber of the bucket, substantially as described.

2. In a water-elevator, the combination of the cylindrical bucket having oppositely-located inlet and outlet and air openings, and provided with a central chamber, with a carrier chain or belt, and a guide wheel or pulley adapted to enter the central chamber of the bucket, substantially as described.

3. In a water-elevator, the combination of a carrier chain or belt, a water-bucket having a central chamber receiving the chain or belt and valved inlet and outlet openings, and a supporting wheel or pulley adapted to enter the said central chamber, substantially as described.

4. The combination of the elongated bearing or tube having an eccentric projection at its end, and the swinging brake-arm journaled or hung on said projection, with a wheel or pulley adapted to engage with the brake-arm, and the shaft of said wheel passing through the elongated bearing or tube, substantially as described.

In testimony whereof I have hereunto set my hand in the presence of two subscribing witnesses.

C. H. TISE.
